(57) CLAIM

The ornamental design for a bow-tie bandana, as shown.

DESCRIPTION

FIG. 1 is a top front right isometric view of a bow-tie bandana laid flat;

FIG. 2 is a bottom rear left isometric view, opposite that of FIG. 1, of the bow-tie bandana;

FIG. 3 is a front view of the bow-tie bandana;

FIG. 4 is a rear view, opposite that of FIG. 3, of the bow-tie bandana;

FIG. 5 is a left view of the bow-tie bandana;

FIG. 6 is a right view, opposite that of FIG. 5, of the bow-tie bandana;

FIG. 7 is a top view of the bow-tie bandana; and,

FIG. 8 is a bottom view, opposite that of FIG. 7, of the bow-tie bandana.

The appearance of any portion of the article between the symbolic break lines forms no part of the claimed design.

1 Claim, 6 Drawing Sheets
